UNITED STATES PATENT OFFICE.

JOHN W. TERRY, OF NEW HAVEN, CONNECTICUT.

SPRING BED-BOTTOM.

SPECIFICATION forming part of Letters Patent No. 739,360, dated September 22, 1903.

Application filed December 12, 1901. Serial No. 85,614. (No model.)

To all whom it may concern:

Be it known that I, JOHN W. TERRY, a citizen of the United States, and a resident of New Haven, county of New Haven, and State of Connecticut, have invented certain new and useful Improvements in Spring Bed-Bottoms, of which the following is a specification, reference being had to the accompanying drawings, forming a part thereof, in which 10 similar letters of reference indicate corresponding parts.

This invention relates to spring bed-bottoms, and has for its principal objects the maintenance of an approximately level spring- 15 surface, while preventing in an economical manner the spring sag at points incurring the greatest load.

With the above and other purposes in view the invention consists, primarily, of a spring 20 bed-bottom in which the spiral coils are connected by a novel arrangement of wires, which while affording diagonally-lateral as well as longitudinal bracing between the coils presents in connection with the latter a highly- 25 effective bed-surface, said bracing being such that while it permits the free individual movement of each coil it so supports the entire series as to normally maintain them level. The bracing referred to further provides in- 30 termediate spaces between the coils of increasing dimension in the direction of the foot of the bed-bottom. This secures in a novel manner transverse zones of the spring- 35 surface of relatively variable rigidity and yield proportionate with the load each is ordinarily designed to support.

There are other novel features and details connected with the present invention, which are also more fully referred to hereinafter.

40 In the accompanying drawings, forming part of this specification, Figure 1 is a plan view of so much of a spring bed-bottom as will suffice to show certain features of my invention. Figs. 2 and 3 are plan views showing, on a larger scale, fragments of the head and foot portions of the improved bottom. Figs. 4 and 5 are inverted side views of the parts disclosed in Figs. 2 and 3, respectively. Fig. 6 is a detail plan view of one of the head 45 fenders and contiguous parts; and Fig. 7 is a transverse section of the parts disclosed in

Fig. 6, taken on the dotted line 7-7 of said figure.

The framing of the improved bed-bottom is presented by the parallel longitudinal bottom 55 strips A, connected and relatively held by transverse end and intermediate braces B, C, and D. Mounted and secured on the framing are spiral springs E, preferably of the familiar inverted shape, the upper coils of which 60 are peculiarly bent, as will presently be more fully explained. These springs are disposed in both longitudinal and transverse rows, as customary, with the exception that the distances between the same increase longitudi- 65 nally at certain points along the bottom and in the direction of the foot thereof.

The upper coils of the springs E, except those of the marginal end and side rows, are bent to present four equidistant offsets e, the 70 several offsets of each spring being in alignment with the corresponding offsets immediately in longitudinal and transverse series therewith. Short longitudinal tie-wires F each pivotally connect a pair of the springs 75 E by having their looped ends f engage the contiguous offsets e thereof, each of said looped ends f also pivotally clamping the central bend f' of a transverse angular tie-rod F', the outer looped ends f'' of which piv- 80 otally engage the depressions e' of springs in the longitudinal series at each side, but in a slightly different transverse plane.

It will be noted that a pair of relatively reversed transverse tie-wires F' are arranged 85 between each longitudinal pair of springs, with their outer looped ends converged and in pivotal engagement with the offsets of the springs in an intermediate transverse plane at each side. By this means the springs are 90 normally supported so that their upper coils will be practically in the same horizontal plane, while the novel disposition of the rods F F' and the depressed character of the offsets e insures connections between the dif- 95 ferent springs, resulting, substantially, in a uniform spring-bearing surface. Obviously as the spaces longitudinally increase between the springs the lengths of the wires F and the angularity of the wires F' are correspond- 100 ingly augmented. Thus the springs and tie-wires F F' are more closely arranged at one

portion of the bed-bottom than at the others, the variation or widening in the relation of the parts being of a graduated character and shown in Fig. 1 as occurring in the direction 5 of the foot. By this means one part of the spring-surface—say from the head to the point indicated by the dotted line x —will be more rigid, and consequently particularly adapted to support the load imposed by the 10 body of the occupant, while the remaining part of the spring-surface will be capable of yielding more readily under the lesser loads incurred, the yield being of graduated character to provide for the diminishing load in 15 the direction of the foot. The spaces between the marginal springs at the sides are spanned by the tie-wires F^2 , which longitudinally connect the springs together by engaging the offsets thereof, the loops f^3 of said wires also 20 clamping yoke-shaped tie-wires F^3 to said springs, while the inner converging members F^4 of said yoke have end loops f^4 engaging the offsets of the nearest spring E in the next parallel longitudinal series. The yoke shape of 25 the wires F^3 provides for the specially peculiar bracing required at the sides, while their rounded outer portions, which interfit with the outer rounded parts of the marginal side springs, conduce to a finished appearance at 30 the sides.

G designates a transverse horizontal rod at the outer side of the head-springs. This rod has end bends G' , which are secured by metal clips g to the upper coil of the oppositely-remote head-springs, while the main transverse portion of the rod is also secured to all the head-springs, the connection with each spring being made by clips $g' g'$, embracing the upper coil at slightly-separated points. That 35 40 portion of each upper head-coil which is between the clips $g' g'$ is embraced by a horizontally-folded section H , of felt, secured in position by a staple h , which passes down through the folds of the felt between the rod and coil portion and is clenched at the under side of the bottom thickness.

The felt-sections H constitute fenders to cushion the contact of the rod G and head-springs with parts of the head of the bedstead.

The rod G has slight depressions immediately beneath the upper folds of the fenders to clear the same.

Slight inward bends g^2 in the rod at appropriate points provide for the proper engagement of the longitudinal tie-wires F^5 , also connecting with the springs E in the transverse series next succeeding the head-springs. The rod G has the additional function of aiding 55 60 in properly maintaining the position of the head-springs.

Transverse tie-wires F^6 F^7 pivotally connect the foot-springs and serve for the anchoring engagement of the outer ends of the longitudinal wires F^8 . It will be noted that inasmuch as one of the ends f^5 of the tie-wires 65 F^9 at the foot pivotally engages the upper coils

of the relatively remote foot-springs at their inner sides the wires F^7 extend across the tops of said remote springs and pivotally engage the upper coils thereof at their outer sides, said springs having a connection with the rest of the system both at their inner and outer sides, thus serving to efficiently brace and support the same with relation to the rest 75 of the spring-bottom. The foot-springs are also provided with fenders. This is attained by securing the ends k of a short transverse section of wire K to the outer portion of the upper coil of each spring at separated points 80 and applying a folded felt-section L to that portion of the coil between such connections and securing it in position by a staple Z' , passing down through both folds between the coil and wire K and clenched beneath the bottom fold. 85

From the foregoing description it will be appreciated that the improved bed-bottom embodying my invention is comparatively light and simple in construction and economically presents a spring-bearing surface involving strength and yielding qualities at different points proportionate with the load to be supported. Moreover, the springs are capable of a free individual movement, while 95 their normal relative positions are assured. Derangement, damage, and noise that might result from movement of parts at the head of the bottom are effectively avoided.

Modifications and changes may be made in 100 the improved bed-bottom without altering the character or departing from the spirit of my invention.

In a copending application filed by me December 12, 1901, Serial No. 85,613, I have disclosed a bed-bottom in some respects similar to that described herein. I do not wish to be understood as making any claim herein of scope and subject-matter corresponding with any claim in said other case. 110

Having thus described my invention, what I claim as new, and desire to secure by Letters Patent, is—

1. In a spring bed-bottom, the combination with a suitable framing, of coiled springs in 115 parallel longitudinal series, the springs of one series alternating with those next adjacent, the spaces between the springs of each series increasing in dimension at different transverse points of the bottom, two pairs of 120 relatively reversed angular tie-wires F^7 , pivotally connected to a pair of transversely-aligned coils of alternating longitudinal series, and pivotally connected at the convergences of their angles to the contiguous coils of the intermediate longitudinal series, by a longitudinal tie-wire also directly connecting said contiguous coils. 125

2. In a spring bed-bottom, the combination with a suitable framing, of coiled springs 130 having longitudinally opposite and side offsets, said springs being in parallel longitudinal series, the springs of one series alternating with those next adjacent, the spaces be-

5 between the springs of each series increasing in dimension at different transverse points of the bottom, a pair of relatively reversed angular tie-wires F' , pivotally connected at their ends to the side offsets of a pair of transversely-aligned coils of alternating longitudinal series, and pivotally connected at the convergences of their angles to the offsets of the contiguous coils of the intermediate longitudinal series by a longitudinal tie-wire also directly connecting said contiguous coils.

10 3. In a spring bed-bottom, the combination with a suitable framing, of springs in parallel longitudinal series, the springs of one series alternating with those next adjacent at each side thereof, bent transverse tie-wires F' connected directly to the springs at each side and having their bends relatively reversed, and a longitudinal wire connecting the 15 springs of the intermediate series and also clamping the central portion of the transverse ties to said intermediate springs.

20 4. In a spring bed-bottom, the combination with a suitable framing, of a marginal series 25 of side springs and an inner parallel series, the springs of which alternate with those of the side series, a yoke-shaped tie interposed between and connected with the side springs and connecting with an inner alternating 30 spring.

25 5. In a spring bed-bottom, the combination with a suitable framing, of a marginal series of side springs and an inner series, the springs of which alternate with those of the side 35 springs, a yoke-shaped tie interposed between and connected with the side springs and having an outer rounded portion conforming with the outer parts of said side springs, said yoke-shaped tie also connecting with an inner alternating 40 spring.

45 6. In a spring bed-bottom, the combination with a suitable framing, of marginal side springs, an inner spring in relation thereto, and a yoke-shaped tie interposed between and connecting with the side springs, said yoke-tie having an outer rounded portion conforming with the outer parts of the side springs, and connected with the inner spring.

7. In a spring bed-bottom, the combination with a suitable framing, of marginal side springs and an inner spring in relation thereto, a longitudinal tie connecting said side springs, and a yoke-shaped tie interposed between with the side springs, having an outer rounded portion conforming with the outer 55 parts thereof, clamped to said springs by the longitudinal tie and connected with the inner spring.

8. In a spring bed-bottom, the combination with a transverse series of vertically-coiled end springs and a parallel row of springs alternating therewith, of a transverse horizontal rod externally in the plane of the upper portions of the end springs and having inward bends g^2 , and angular end portions, the latter secured to the remote springs of the series, the body of the rod being secured to the outer parts of the upper coils of the end springs, and the alternating springs being connected by longitudinal ties F^6 , with the 70 bends g^2 , of the rod and by transverse braces with the contiguous end springs.

9. In a spring bed-bottom, the combination with end and alternating wire springs, of transverse angular ties connected with opposite parts of the end springs, straight ties connecting with the outer side of the corner spring of the end series and with the corresponding side of the adjacent end spring, a longitudinal tie clamping the angular tie to 80 the inner spring and anchored to the straight transverse tie.

10. In a spring bed-bottom, an end spring having a short section of wire connected at its ends to separated points of the spring-coil, 85 a section of yielding material secured to said coil by a fastening device passing between said coil and short section of wire.

In testimony that I claim the foregoing as my invention I have signed my name, in presence of two witnesses, this 2d day of December, 1901.

JOHN W. TERRY.
